[57] CLAIM

The ornamental design for a combined food grater and grinder, as shown and described.

DESCRIPTION

FIG. 1 is a top, front, right side perspective view of a combined food grater and grinder showing my new design;

FIG. 2 is a top plan view thereof;

FIG. 3 is a side elevation view thereof, the remaining sides
being identical;

FIG. 4 is a bottom plan view thereof;

FIG. 5 is a perspective view thereof in an alternate position;
FIG. 6 is a top, front, right side perspective view of an alternate embodiment of the combined food grater and grinder of FIG. 1 showing my new design;

FIG. 7 is a top plan view of FIG. 6;

FIG. 8 is a side elevation view of FIG. 6, the remaining sides
being identical;

FIG. 9 is a bottom plan view of FIG. 6; and,

FIG. 10 is a perspective view of FIG. 6 in an alternate position.
